(57) **CLAIM**

The ornamental design for a “game scoreboard,” as shown and described.

DESCRIPTION

FIG. 1 is a perspective view of a game scoreboard showing my new design;

FIG. 2 is an enlarged scale perspective view thereof, with the bottom upright post being broken away for ease of illustration;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a top plan view thereof; and,

FIG. 8 is a bottom plan view thereof.

It is understood that the top display board discloses an undetermined height. The broken lines are for illustrative purpose only and form no part of the claimed design.
